(57) **CLAIM**

The ornamental design for a card wallet as shown and described.

DESCRIPTION

FIG. 1 is a perspective view of a card wallet, showing a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the card wallet showing a second embodiment of our new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a perspective view of the card wallet showing a third embodiment of our new design;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The dash-dash broken lines in the drawing figures depict portions of the card wallet that form no part of the claimed design.

The dot-dash broken lines shown in FIGS. 1-3, 8-10, and 15-17 depict stitching which form a part of the claimed design.

1 Claim, 21 Drawing Sheets
